UNITED STATES PATENT OFFICE.

CHARLES J. B. BORGESON, OF SYRACUSE, NEW YORK.

LUBRICATING ATTACHMENT FOR METAL-WORKING MACHINES.

1,273,996.

Specification of Letters Patent. Patented July 30, 1918.

Application filed March 8, 1917. Serial No. 153,258.

To all whom it may concern:

Be it known that I, CHARLES J. B. BORGESON, a citizen of the United States, and a resident of Syracuse, in the county of Onondaga and State of New York, have invented a certain new and useful Lubricating Attachment for Metal-Working Machines, of which the following is a specification.

This invention has for its object a lubricator for metal working machines as screw machines, and the like in which the tools work in oil, which lubricator is particularly simple in construction and highly efficient and durable in use; and the invention consists in the combinations and constructions hereinafter set forth and claimed.

In describing this invention, reference is had to the accompanying drawings in which like characters designate corresponding parts in all the views.

Figure 1 is an elevation, partly in section, of one embodiment of my lubricator.

Fig. 2 is a view similar to Fig. 1 of another embodiment thereof.

Fig. 3 is a detail view of the detached feed pipe.

Figs. 4 and 5 are transverse sectional views through one of the nozzles and the feed pipe, the nozzles being shown in different positions in said figures.

This lubricator for metal working machines comprises generally, a feed pipe, and a plurality of nozzles associated with the feed pipe, the feed pipe and each individual nozzle having coacting means for opening and closing communication through said nozzle independently of the other nozzles.

1 designates the feed pipe which is here shown as carried by a support, such as a coupling 2, through which the lubricating oil is fed to the pipe 1, the support 2 threading on a suitable feed pipe not shown.

3 designates a series or a plurality of nozzles mounted on the feed pipe and as here shown, the nozzles are provided with hubs 4 sleeved on the pipe, the hubs abutting one against the other, each nozzle having a passage 5 designed to register with an outlet passage or opening 6 in the feed pipe 1.

As here shown, the feed pipe is formed with a plurality of outlets along one side as the lower side thereof, one for each nozzle 3, instead of one continuous outlet slot, and the nozzles are movable about the axis of the pipe to carry the passages 5 into and out of

registration with the outlets 6 of the feed pipe 1.

The hubs of the nozzles are interposed between spaced apart abutments on the pipe 1, and as here shown one of these abutments 60 is the end face of the hub 7 of the coupling 2, and the other abutment is a disk or shoulder 8 secured to the end of the pipe by means of a screw 9.

The hubs 4 are slidably mounted on the feed pipe 1, and means as a spring 10 is employed to press the nozzles along the pipe toward the abutment 7, this spring being interposed between the disk 8 and the hub 4 of the opposing nozzle 3. The feed pipe is 70 adjustably mounted in the coupling 2 in order that it may be turned to change the position of the outlet opening 6 and as here shown said pipe is held in its adjusted position by means of a screw 11 threading in the 75 hub 7 of the coupling and having a reduced end 12 which enters one of a series of holes 13 in the pipe. These holes 13 are part of a series of holes through which the oil passes from the coupling into the feed pipe. Also 80 by reason of the screw 11, the coupling 2 can be arranged at an angle in order to be most conveniently connected to the source of supply.

Usually the feed pipe is arranged with its 85 outlets 5 along the lower side thereof but in some instances, it may be desirable to slightly rotate the pipe so that the openings are on the front or other side thereof.

In any position of the pipe upon rotation 90 of a nozzle 3, communication can be cut off or established through said nozzle.

In Fig. 1, the coupling 2 is shown as located midway between the ends of the feed pipe and the nozzles on opposite sides of 95 the coupling. Also there is an abutment 8 and spring 10 at each end of the feed pipe. In Fig. 1, the end nozzles are shown as in operative position while the other nozzles are shown as turned upwardly so that no oil 100 can pass therethrough.

One of the nozzles at the right hand side of the nozzle 2 is shown as formed with an extension 14.

In Fig. 2, the coupling 15 is shown as 105 mounted on one end of the feed pipe 16 and as secured thereto by a screw 17 threading through the hub of the coupling and into the end of the pipe or a plug in the end of said pipe.

In Fig. 2 a sleeve 18 is interposed between the coupling and the hub of the nearest nozzle, this sleeve 18 serving as an abutment toward which the spring 16 presses the nozzles.

In use, in metal working machines in which the work or cutting is done in lubricating oil some classes of work do not require as many tools as others, and hence it 10 is not necessary to use as many nozzles. By my invention, the oil through the unnecessary nozzles is readily turned off by merely turning up the nozzles so that the passages 5 thereof are out of registration with the outlet openings 6 of the feed pipe.

What I claim is:

1. A lubricator for metal working machines comprising a feed pipe having an elongated circumferentially extending slot, a 20 nozzle mounted on the feed pipe and having a discharge opening of smaller diameter than the length of the slot and movable about the pipe to different radial angles thereto with its discharge opening in full 25 registration with the slot at different angles of said nozzle and being movable completely out of registration with the slot to close the slot, substantially as and for the purpose described.

30 2. A lubricator for metal working machines comprising a feed pipe, nozzles mounted on the feed pipe and having a discharge opening, the nozzle being movable about the pipe and having a discharge opening arranged to receive the full amount of 35 lubricant therefrom when arranged at various angles relatively to the pipe and being additionally movable relatively to the pipe to cut off the communication between the 40 pipe and the nozzle, substantially as and for the purpose specified.

3. A lubricator for metal working machines comprising a feed pipe and a plurality of nozzles mounted on the feed pipe 45 and rotatable about the same independently of each other, the feed pipe having openings discharging into the nozzles and the nozzles having discharge openings arranged to come in full registration with the openings of the 50 pipe at various angles of the nozzles and to close said openings in the pipe upon additional rotation, substantially as and for the purpose described.

4. A lubricator for metal working machines comprising a feed pipe, a plurality of 55 nozzles rotatably and slidably mounted on the feed pipe, the feed pipe and the nozzles having openings, each nozzle being rotatable about the feed pipe for carrying its opening

into and out of registration with the opening of the feed pipe, an abutment for the nozzles, and means tending to press the nozzles toward the abutment, substantially as and for the purpose set forth.

5. A lubricator for metal working machines comprising a feed pipe, a plurality of nozzles rotatably and slidably mounted on the feed pipe, the feed pipe and the nozzles having openings, each nozzle being rotatable about the feed pipe for carrying its opening 60 into and out of registration with the opening of the feed pipe, an abutment for the nozzles, and a spring acting on one of the end nozzles and tending to slide the nozzles toward the abutment, substantially as and 65 for the purpose described.

6. A lubricator for metal working machines comprising a feed pipe having a pair of spaced apart abutments thereon, a plurality of nozzles rotatably and slidably 70 mounted on the feed pipe between the abutments, the feed pipe and each nozzle having openings and each nozzle being movable about the feed pipe to carry its opening into and out of registration with the opening of 75 the feed pipe, and a spring between the one of said abutments and the contiguous nozzle, substantially as and for the purpose specified.

7. A lubricator for metal working machines comprising a feed pipe, a support therefor, a plurality of nozzles associated with the pipe, the pipe being rotatably mounted in its support to change the direction of the nozzles when the nozzles are in 90 their operative position, and means for holding the feed pipe in its adjusted position, substantially as and for the purpose set forth.

8. A lubricator for metal working machines comprising a feed pipe, a support for the feed pipe, the feed pipe having its outlets along one side thereof, nozzles mounted on the pipe and adjustable about the same, each nozzle being movable independently of 100 the others about the pipe to carry its opening into and out of registration with an outlet of the feed pipe, the feed pipe being rotatably mounted in its support to change the 105 position of the outlets thereof, and means for holding the pipe in its adjusted position, substantially as and for the purpose described.

In testimony whereof, I have hereunto signed my name, at Syracuse, in the county 115 of Onondaga, and State of New York, this 6th day of Feb., 1917.

CHARLES J. B. BORGESON.
